DEODORANT CAN

John Coyle, Baltimore, Md., assignor to Continental Can Company, Inc., New York, N. Y., a corporation of New York

Application March 16, 1945, Serial No. 583,095

2 Claims. (Cl. 299—20)

1

The present invention relates, generally stated, to that class of article usually termed in the trade by the name of a deodorizing device for household use.

At the present time there are a number of devices being manufactured in which a wick is inserted in the neck of a bottle or similar receptacle containing a deodorizing material. In devices of this kind the wick is pulled out of the neck of the bottle in upright position, but it has been found that an insufficient amount of the liquid is evaporated to thoroughly deodorize the room in which it is used.

An important object of the invention, therefore, is to provide a deodorizing device in the form of a can provided with a large area of absorbent material, said can being adapted to be inverted when in use so as to evaporate a greater amount of liquid in a given interval of time.

Another object of the invention is to provide a deodorant can in which the waste of deodorizing material is reduced to a minimum while at the same time obtaining maximum benefit from the material when the can is in use.

A further object of the invention is to provide a deodorant can comprising dual detachably connected sections packaged for sale to the customer, one section forming a receptacle for the deodorizing material that is initially sealed by closure means and the other section forming a vaporizer that is provided with a depressed bottom carrying a fabric disk adapted to be exposed to the deodorizing material after the removal of the closure means and when the can is placed in an inverted position. The other section is also provided with a series of perforations formed annularly thereof through which the deodorizing fumes or vapors escape into the room after exposure to the fabric disk.

The above and other objects of the invention will in part be obvious and will be hereinafter more fully pointed out.

In the drawing:

Figure 1 is a side elevational view, partly in section, of a deodorant can embodying the features of the present invention, the can being shown in the manner in which it is assembled for sale to the customer.

Figure 2 is a fragmentary side elevational view, partly in section, of the can in an inverted position and illustrating the manner in which it is used.

Figure 3 is a fragmentary sectional view of a modified form of the invention.

Referring to the drawing for a more detailed description thereof, the new and improved deo-

2

dorant can is generally designated by the reference numeral 5 and is shown to include a pair of sections 6 and 7. The sections 6 and 7 are preferably formed of a material of the type generally used in the manufacture of cans, the section 6 being shaped somewhat in the manner of a cone top can for packaging beer. The section 6 comprises a cylindrical shaped body 8 formed with seams 9 and 10, the upper end of the body being cone-shaped as indicated at 11, having a neck 12 sealed with a standard crown closure 13 that is press fitted on the neck.

The upper section 7, hereinafter termed a vaporizer, comprises a cylindrical wall or body 14 having a lower beaded end 15. The upper end of the vaporizer 7 is sealed by means of a dome-shaped closure member 17, said member having an annular wall portion 18 fitted within and in sealing engagement with the body portion 14 and double seamed to the upper end 15 thereof as indicated at 19. The central-most portion of the dome-shaped closure member 17, which normally overlies the crown cap 13, is flattened as indicated at 20 so as to avoid a pool of liquid below the mouth of the neck 12 and the fabric when the can is in an inverted position as will be herein-after more fully described.

Adhesively or otherwise secured on the inner face of the end 17, there is a fabric disk 21 adapted to be positioned over the crown cap 13 when initially assembling the deodorant can as shown in Figure 1 of the drawing. The fabric disk 21 follows the general contour of the dome-shaped end 17 and is appreciably larger than the opening of the neck 12 with the neck being positioned centrally of the disk. Thus the disk will become thoroughly saturated, after removal of the closure 13 and upon inverting the device, so as to obtain maximum benefit from the deodorizing material. It will be noted that the central-most portion of the fabric disk which is in contact with the crown cap 13 is slightly compressed and therefore the outer marginal edges of the disk are of greater thickness than the central-most portion on that area of the disk which is compressed by reason of its contact with the cap.

The lower end of the vaporizer 7 is crimped to form an inwardly extending annular flange 22 adapted to be held in frictional engagement with the seam 10 through the locking dimples 23 which snap over this seam during placement and removal of the vaporizer 7. The area between the flange 22 and dimples 23 snugly engages the periphery of the seam 10 and thereby the vaporizer 7 is firmly united with section 6.

A series of perforations 24 are formed annularly of and in spaced relation in the body wall 14 to permit escapement of the fumes of the deodorizing material absorbed by the fabric disk 21.

The deodorant can would be initially assembled and packaged for distribution to the customer in the manner shown in Figure 1 of the drawing. The deodorizing material contained within the section 6 would be effectively sealed through the medium of the crown cap 13 or other type of closure. The directions for consumer use are extremely simple. In order to use the can it is necessary to first remove the crown cap 13, and to accomplish this the section 6 and vaporizer 7 are separated by an outward pull on either or both elements which allows the dimples 23 to snap out of engagement with the seam 10. After disconnecting the sections, the crown cap 13 is removed and the vaporizer 7 is placed in its initial position on the section 6. Removal of the crown cap 13, however, will bring the fabric disk 21, when vaporizer 7 is replaced, into direct contact with the mouth of the neck 12 so that when the can is inverted to the position shown in Figure 2 of the drawing, the deodorizing material will flow out of the neck opening onto the fabric disk. The flattened area 20 of the dome-shaped end 17 will hold the lower level of the liquid within the can at the level of the neck opening, thus avoiding a pool of liquid below the mouth of the neck opening which would otherwise result from having a convex dome unbroken by a flat surface. The flat area 20 will maintain the fabric disk in contact with the periphery of the neck opening, thereby preventing the liquid from rising outside the neck above the level of the mouth opening. There is, of course, provided a bead 25 around the opening of the neck 12 so that the fabric disk 21 is held lightly thereagainst. The liquid flowing from the section 6 onto the fabric disk 21 will vaporize and the fumes therefrom will enter the room through the perforations 24. As rapidly as the liquid evaporates air will pass through the fabric disk 21 into the section 6 to displace the liquid consumed.

The deodorant can may be placed in its inverted position on a table or flat surface. However, in some instances it may be desirable to suspend the can from a hook or the like. To permit suspension of the can there is provided a looped ring 26 extending vertically from the beaded or coiled end 16, the free ends of the looped ring being carried and rigidly held within the beaded end 16. The looped ring 26 is formed of wire or similar material and is attached to the vaporizer 7 during the fabrication thereof.

In the modified form of the invention shown in Figure 3, the end 17 is formed with an interrupted bead 26 near the edge of the fabric, the bead being preferably in six segments. A series of annularly spaced perforations 27 are also formed in the end 17 in close proximity to the flattened area 20, and a second series of perforations 28 are formed in the double wall section 29, these latter perforations communicating with the atmosphere. The bead 26 functions to hold the fabric disk out of contact with a portion of the end 17 and the perforations 27 allow the evaporation from this portion to enter the room through the perforations 28. Thus the fabric disk will absorb and evaporate a still greater amount of the deodorant material in a given interval of time in this form of the invention, the use of which is the same as in the previously described form.

From the above description when taken in connection with the accompanying drawing it will be seen that there has been provided a deodorant can comprising a pair of sections in the form of a can that are detachably connected one to the other. The sections are assembled in a manner permitting free and easy detachment when the deodorant can is to be used by the consumer. However, if the deodorant within the section 6 is not to be continuously used until the contents thereof have been exhausted, the can will be returned to the position shown in Figure 1 and the fabric disk 21 will constitute a satisfactory closure preventing further vaporization of the deodorant. As before indicated, the vaporizer 7 is shaped to permit the deodorant can to be placed in its inverted position on a table or flat surface in the room or it may be suspended by means of the looped wire ring 26. In either case the fumes from the deodorizing material absorbed by the fabric disk 21 will escape into the room through the annular perforations 24.

It is to be clearly understood that various changes in the details and construction and arrangement of parts may be made without departing from the scope of the invention and set forth in the appended claims.

I claim:

1. A deodorizing device comprising a cylindrical shaped can having a cone-shaped upper end defining an opening with a closure member thereon, a seam for uniting the cone-shaped end with the body wall of said can, said can forming a receptacle for a deodorizing material, a vaporizer having an open end detachably connected to said seam, a dome-shaped end wall in said vaporizer, a fabric disk carried by said dome-shaped end, said dome-shaped end having a flattened portion centrally thereof for maintaining said fabric disk in contact with said closure member, said vaporizer adapted to be detached from said can to remove said closure member and when replaced thereon said fabric disk will be held by said flattened portion in contact with the mouth of said opening, whereby upon inverting said device the deodorizing material will flow onto said fabric disk and be absorbed thereby, the fumes therefrom being discharged through perforations formed in the vaporizer.

2. A deodorizing device comprising a cylindrical shaped can having a cone-shaped upper end defining an opening with a closure member thereon, a seam for uniting the cone-shaped end with the body wall of said can, said can forming a receptacle for a deodorizing material, a vaporizer having an open end detachably connected to said seam, a dome-shaped end wall in said vaporizer, a fabric disk carried by said dome-shaped end, said dome-shaped end having a flattened portion centrally thereof for maintaining said fabric disk in contact with said closure member, an interrupted bead formed in said dome-shaped end and spaced radially from the flattened portion thereof for holding a portion of the fabric disk out of contact with said end wall, said vaporizer adapted to be detached from said can to remove said closure member and when replaced thereon said fabric disk will be held by said flattened portion in contact with the mouth of said opening, whereby upon inverting said device the deodorizing material will flow onto said fabric disk and be absorbed thereby, the fumes therefrom being discharged through perforations formed in the vaporizer.
